SUCKER-ROD HANGER

Application filed April 15, 1925. Serial No. 23,296.

This invention relates to a device termed a sucker-rod hanger adapted to be employed in oil well drilling apparatus for hanging or supporting sections of sucker rods employed in the operation of the wells in the well derrick.

An object of the present invention is to provide a sucker rod hanger with a hook for supporting the hanger having a normally closed safety member, and an object is also to provide an additional suspending member for the hook adapted to automatically retract the latch from the hook of the hanger to facilitate securing the hanger to a supporting means.

Another object of the present invention is to provide a form of sucker rod hanger with a plurality of chains mounting the rod gripping clamps, the chains being mounted upon a two-part body, the lower part being adapted to act as a receiver for the chains when the hanger is not in use, and preferably constructed to serve as a chamber holding a material for rinsing the chains and preventing the same rusting.

Various other objects and advantages of the present invention will appear from the following description of a preferred form of sucker rod hanger embodying the invention. For this purpose reference is made to the accompanying drawings, in which a preferred example of the sucker rod hanger is illustrated.

In the drawings:

Fig. 1 is a front elevation.

Fig. 2 is an elevation mainly in vertical section.

Fig. 3 is an elevation on a smaller scale of the hanger with the lower part of the body removed, and the chains extending to operating position.

Fig. 4 is a front view of one of the clamping members secured to the chains, and

Fig. 5 is a view at right angles to Fig. 4.

Referring to the drawings the sucker rod hanger there illustrated comprises a main supporting member 2 preferably in the form of an inverted hook 3 having a downwardly extending shank 4. 5 indicates a safety latch or guard normally closing the mouth of the

hook, the latch or guard 5 being pivoted as at 6 to a bracket 7 of the shank 4 of the hook. 8 indicates a spring normally urging the guard 5 into the closed position. The guard 5 has opposed side walls 9 extending to the opposite side of the shank 4 and there are secured together by a bolt 10 pivotally mounting an auxiliary supporting member 11. This member may be of any desired shape terminating in a loop 12^a as indicated in Fig. 1, and is provided with a cam part 12 engageable with the shank 4 when the supplemental supporting member 11 is pivoted to the upward or supporting position. The action of this cam 12 is to pull the guard 5 into the open position enabling the hook 3 to be readily engaged with the supporting device and locked therein by the release of the auxiliary suspending member 11.

The main suspending member 2 additionally supports a two-part body 12^b, the upper portion 13 of which is conical in form, the apex 14 of the cone fitting the shank 4 of the member 2 and the base of the cone being riveted to a base plate 15 having an opening 16 through which the shank 4 passes. The end of the shank 4 passing below the base plate 15 carries a nut 17 engaging the base plate for supporting the body thereon.

18 indicates a hood riveted to the conical part 13 of the body and angled outwardly therefrom. The hoods 18 support the upper part of the conical body on the chain container hereafter described and prevent excessive tangling of the chains which would occur if the conical body passed further into the chain container. To the lower end of the conical body 13 is secured a number of chains 19 which at their ends each separately support a clamping member 20. These chains and clamping members 20 are adapted to be coiled up and carried in the lower body part 21 of the hanger which is in the form of a cylindrical container suitably secured to the body part 13 as by clamps 22.

The clamping members 20 each include a main clamping part 23 having an opening 24 at their ends by which they are secured to the chains and having a gripping curved groove 24^a at their other end cooperating with the

grooved straight face 25 of a cooperating clamping part 26, the cooperating clamping part being pivotally secured as by a bolt 27 to the clamping part 23. Clamping members 20 in operation serve to support or suspend rods which are part of a pumping apparatus. In oil wells a well is frequently pumped by plunger pumps which may be located several thousand feet below the surface of the well and it is frequently necessary to remove the plunger and rods from the well. When this is done about every thirty to sixty feet of the rod is unclamped and such a section is received by one of the clamps 20 and supported by the device of this invention. It will be readily seen that the two surfaces of the clamps provide a means for positively gripping the rods when they are suspended on the device.

With the herein described sucker rod hanger, when the hanger is not in active use, the lower body part 21 can be filled with a light-weight oil which will maintain the chains 19 and clamps 20 clean and in proper condition for use, and prevent their rusting. Moreover, the two-part body construction permits the sucker rod hanger to be readily transposed, despite its long depending chains, in a compact space ready at all times for instant use.

In use, the hanger is hoisted to the point in the derrick where it is to be suspended by a rod secured to an auxiliary suspending member 11; the raising of the hanger in this manner removes the safety guard 5 to the open position and at the arrival of the hanger at the upper end of the derrick it may be readily suspended in its intended operating position. The member 11 is considered as an auxiliary supporting member since this member is used to support the device, or at least the device excluding parts 21 nearest operations. When the device is supported on member 11 it will be noticed that the cam 12 automatically opens the latch for hook 3. Then by a release of the member 11 the guard 5 will automatically close across the mouth of the hook 3, and the hanger is safely suspended in place. Each of the clamps 20 secured to the chain 19 may then be employed to support or suspend a section of sucker rod or the like in the well derrick, as is well understood in the art.

While the embodiment of the invention herein described is well suited for accomplishing the purposes of the invention, it is to be understood that various modifications may be made in the details of the invention without departing from the spirit and scope thereof, and the invention is therefore of the scope of the appended claims.

I claim:

1. In a device of the class described, the combination of a safety hook, means comprising a two-part body supported by the

hook for carrying a plurality of chains, the lower part of the body being detachable while in use, a rod gripping clamp mounted on the end of each chain, the lower part of said two-part body being adapted to act as a receiver for the chains when the hanger is not in use. 70

2. In a device of the class described, the combination of a safety hook, a two-part body supported by the hook, one part being of conical shape and adapted to support at its lower end a plurality of chains, each chain carrying a rod gripping clamp, the other part being adapted to be removably attached to the first of said parts and to provide a container in which the chains may be coiled or retained 80 to provide a chamber for rinsing the chains and preventing their rusting. 75

3. In a device of the class described, an inverted hook member having a depending shank, a conical body through which said shank axially extends, the shank having means at its lower end for engaging and supporting said body, a plurality of chains attached to the body at circumferentially spaced apart points around its lower ends, 85 and a rod gripping clamp secured to each chain. 90

4. In a device of the class described, an inverted hook member having a depending shank, a conical body through which said shank axially extends, the shank having means at its lower end for engaging and supporting said body, a plurality of chains attached to the body at circumferentially spaced apart points around its lower ends, 95 a rod gripping clamp secured to each chain, a supplemental supporting member for the device, a latch for said hook member, a means connecting said latch with said supplemental supporting member operative to actuate the latch to the open position upon supporting the device upon the supplemental supporting member. 100

Signed at Calexico, Calif., this 31st day of March, 1925.
